EMERGENCY ELECTRIC GENERATING SET

Joseph P. Bryan, Troy, Pa.

Application July 7, 1930, Serial No. 465,866
Renewed August 21, 1934

9 Claims. (Cl. 290—7)

This invention relates to emergency electric generating units.

In many instances it is desirable, and even necessary, that an auxiliary or emergency electric generating set be in readiness to supply current when the main source of electricity fails for any reason. As an instance of this, the lights in moving picture theatres and other places of public gathering are usually lighted from the supply mains for the city, which mains are usually laid along the streets and receive their electricity from a central generating station. If such a source of supply of electricity to the theatre or other place of public gathering, is discontinued because of failure at the central station, or disconnection or failure of the supply lines, the place of gathering would be left in darkness. In case of fire the supply lines are apt to be disconnected by the ravages of fire or by the action of the firemen. In some localities it is a rule that the first duty of the firemen on reaching a fire is to disconnect all connection of the fired building with the electric supply mains. This, of course, extinguishes all the electric lights in the building including the exit lights, and in time of fire the people left in darkness not knowing which way to turn, are likely to become involved in a panic with consequent disaster. Many actual occurrences have taken place wherein large numbers of people have been seriously injured and even killed because of failure of the lights in time of fire.

It has been proposed to provide an emergency generating set to supply electricity in place of the regular source, and on account of the fact that substantially all buildings are provided with water mains under pressure, so that a source of power is thus supplied in substantially all instances, it has been proposed to utilize the usual water mains in a building as a source of power for driving an emergency electric generator set to supply electricity when the main source of supply fails. Such sets have been quite extensively used in practice and have given satisfactory service at least to the extent of supplying the exit lights with current so that panic conditions, as referred to, have been avoided.

In such sets the water motor for driving the generator has been controlled by a valve operated in response to current in the main supply lines. This is effected by causing the valve to be held closed by an electromagnet receiving its energizing current from the supply mains, such valve being opened when it is released by the electromagnet becoming deenergized, as when the main source of current supply fails. In order

that the set may properly perform its functions and meet the emergency of the failure of the main supply of electric current, it is necessary that the valve controlling the water wheel should certainly operate at the proper time. Any failure to so operate might obviously be attended by disastrous consequences. A needle nozzle for the water wheel, i. e. a nozzle through which the water is supplied to the wheel containing a needle valve, affords a readily adjustable and satisfactory means of regulation of the water supplied to the wheel. The needle valve is, however, peculiarly liable under some circumstances, after it has been seated upon its seat, to become stuck thereto, as for instance by corrosion incident to infrequent operation of the set. When, therefore, the needle valve is relied upon to shut off the water from the wheel, thus rendering necessary its seating upon its seat, the needle valve is peculiarly liable to become stuck and not open at the desired time. Such valve, however, has peculiarly valuable regulating properties as above referred to.

It is the main object of the present invention to provide a hydro-electric emergency generating set with a desired regulating valve for the water wheel and also means for shutting off and admitting water to the water wheel which shall be certain in operation and free from the objections as noted. To this end a valve peculiarly adapted for regulating purposes, but which is never seated is employed for regulation, while a valve of a different type, is employed for shutting off the supply of water to the water wheel.

It is therefore a further object of the invention to provide a hydro-electric emergency generating set wherein one type of valve is used for regulating the water supply to the water motor and another type of valve is employed for shutting off the supply of water to that motor. A needle valve is peculiarly adapted for regulating purposes, while a different type of valve, such as a gate valve or a globe valve, is less liable to become stuck to its seat by corrosion or otherwise; and it is therefore a further object of the invention to provide a hydro-electric emergency lighting set wherein the water supplied to the wheel is regulated by a needle nozzle, while it is never seated and so cannot become stuck to its seat, the supply of water to the wheel being shut off or turned on by means of a different type of valve.

Other and ancillary objects of the invention will appear hereinafter.

In the accompanying drawings which illustrate the invention—

Fig. 1 is a diagrammatic view of apparatus embodying the invention; and

Fig. 2 is a vertical section transverse to the shaft of the water wheel showing the arrangement of the valves and regulating means with relation to the water wheel.

Referring to the drawings, the apparatus comprises a water wheel 1 of the impulse or any other suitable type, the shaft 2 upon which the runner of the water wheel is fixed, extending to the direct current electric generator 3, the armature of the generator being fixed on the shaft 2 which is continuous between the runner of the water wheel and the armature of the generator. The water for operating the wheel is introduced through a nozzle 4 controlled by a needle valve 5, the stem 6 of which is secured to a yieldable diaphragm 7 of rubber or other suitable material forming a fluid-tight partition separating the casing 8 into the fluid-tight chambers 9 and 10. The stem 6 continues on through the diaphragm 7 and has secured to it at one end, the plate 12 having the compression spring 11, interposed between it and the casing 8. This spring is under compression so it tends to withdraw the needle valve 5 from the nozzle opening and so increase the size of that opening, and so the supply of water to the water wheel. Water under pressure is supplied from the usual house water main 13 through the pipe 14, the globe valve 15 and the pipe 16 to the junction 17. From this junction water is led by the pipe 18 to the chamber 9. Also from the junction 17 the pipe 19 leads into the chamber 20 whence the nozzle opens into the water wheel. The parts are so adjusted that the needle 5 can never be forced against or seated in the nozzle. The pressure of the water in the chamber 9 tends to force the diaphragm 7 against the tension of the spring 11 and so move the needle valve 5 further into the nozzle 4, so as to decrease the opening in the nozzle, and the supply of water to the turbine. It will thus be seen that the water delivered to the turbine through the nozzle is regulated according to the pressure of the water, the needle valve being withdrawn from the nozzle by the spring to thereby increase the opening in the nozzle. Conversely the needle valve will be moved to decrease the nozzle opening as the pressure of the water supply increases.

The shutting off of the water supply from the water wheel is controlled by the globe valve 15 and it is completely closed in order to entirely shut off the water. Conversely the water is permitted to be supplied to the wheel when the valve 15 is open. The opening and closing of the valve 15 is accomplished by means of a hydraulic cylinder 21 which is actuated in response to the energization and de-energization of an electromagnet 22 which has the terminals of its coil connected to the main or street supply electric mains 23 and 24. When current is on those mains and the electromagnet 22 is consequently energized, its plunger 25 will be attracted upwardly against the compression spring 26. The lower end of the plunger 25 has pivoted to it a link 25' which link is also pivoted to the arm 27 fixed upon the rotatable valve spindle 28. Upon this spindle is also fixed the valve member 29 which makes fluid-tight contact with the valve casing 30. With the plunger 25 raised, the arm 27 and valve member 29 will occupy the position as shown in dotted lines in Fig. 1. The water

main 13 which is connected with the port 31 will be connected through that port and the port 32 and the pipe 33 with the cylinder 21 above the piston 34. At the same time the portion of that cylinder below the piston 34 will be connected through the pipe 35, the valve port 36 and the valve port 37 with the drain pipe 38. Under these conditions the piston 34 will be forced downwardly, carrying with it the piston rod 39 which carries the movable valve member 40, and the valve member 40 will be forced against its seat thereby closing the valve and shutting off the water supply from the water wheel.

If, however, the current supply on the mains 23 and 24 should fail, the electromagnet 22 being thereby deenergized, the plunger 25 will be forced downwardly by the spring 26 and the valve member 29, will occupy the position as shown in the full lines in Fig. 1. The valve ports 31 and 36 will then be connected so that the cylinder below the piston 34 will be connected with the water supply main 13, while that portion of the cylinder above the piston will be connected through the ports 32 and 37, with the drain pipe 38. The piston will, therefore, rise and will carry with it the movable valve member 40 thereby opening the valve and admitting water from the main to the water wheel.

It will now appear that when current is supplied by the mains 23 and 24 water will be shut off from the water wheel and the generating set will be at rest. If, however, the mains 23 and 24 should fail to supply current, the valve 15 will be opened and the generating set will be started up.

Normally the consumption circuit including the conductors 41 and 42 and the lamps 43 or other translating device are to be connected with and derive their current from the main supply lines 23 and 24. Upon failure of current in the supply lines, however, the hydro-electric generator set is started up as just described and supplies current to the consumption circuit. In order that the consumption circuit may be normally connected with the main supply conductors and that the connections of that circuit may be changed to connect with the generator of the emergency generating set upon failure of current in the main supply conductors, switching apparatus may be provided as will now be described.

The conductors 41 and 42 are respectively connected with the contacting switch blades 44 and 45 which switch blades are pivoted at 46 and 47 and are connected together by an insulating link 48 which is pivoted at its ends to the blades 44 and 45. The conductors 23 and 24 are respectively connected by the conductors 49 and 50 with the stationary switching contacts 51 and 52. Other stationary switching contacts 53 and 54 are respectively connected by the conductors 54 and 55 with the terminals of the generator 3. The piston rod 39 extends upwardly through the upper end of the cylinder and at its upper end has fixed to it a lateral projection 56 which, on its downward stroke, is adapted to engage with the horn 57 of the forked end of the blade 45, and throw the switch into the position as indicated in dotted lines, while on its upward stroke it is adapted to engage the horn 58 to throw the switch into the position as indicated in full lines. It will thus be apparent that when the piston is in its lowermost position, which is the case when current is being supplied by the mains 23 and 24, that the switch blades 44 and 45 will be in the position as

indicated in dotted lines when the consumption circuit will be connected with the main supply conductors 23 and 24. When, however, current fails on the conductors 23 and 24, the piston 34 will be in its uppermost position, and the switch will be in the position as indicated in full lines when the consumption circuit will be connected with the terminals of the emergency generator.

It will now be apparent from the foregoing that when the main line conductors are energized the consumption circuit will be supplied therefrom and the water supply will be cut off from the water wheel of the emergency generating set which will therefore be at rest. When, however, current on the main supply mains fails water will be supplied to the water wheel and the generator set in operation, and at the same time the consumption circuit will be disconnected from the main supply conductors and connected with the terminals of the generator. During this operation the supply of water to the water wheel will be regulated according to the pressure of the water by means of a needle nozzle which, however, is never closed or seated, this function being performed by the valve 15 which is of a type not liable to stick and fail of operation, and at the same time the peculiarly valuable regulating qualities of the needle valve are availed of.

When the mains 23 and 24 again become energized the valve 15 will be closed, thereby shutting off the water supply from the water wheel and the switching mechanism will be operated so that the consumption circuit will be disconnected from the generator of the emergency set and connected with the main supply conductors 23 and 24.

While the invention has been illustrated in what is considered its best application it may have other embodiments without departing from its spirit and is not therefore limited to the structures shown in the drawings.

What I claim is:

1. In an emergency electric generating set, the combination with an electric generator of a fluid pressure operated motor, driving connections between said motor and generator, a conduit conducting fluid to said motor, a valve in said conduit to shut off the supply of fluid to said motor, a circuit, means for operating said valve in response to voltage conditions in said circuit, and a fluid-pressure-controlled valve responsive to fluid pressure in said conduit between said valves for regulating the fluid supplied to said motor.

2. In an emergency electric generating set, the combination with an electric generator of a fluid pressure operated motor driving connections between said motor and generator, a conduit conducting fluid to said motor, a valve in said conduit to shut off the supply of fluid to said motor, a circuit, means for operating said valve in response to voltage conditions in said circuit and a needle valve responsive to fluid pressure in said conduit for regulating the fluid supplied to said motor.

3. In an emergency electric generating set, the combination with an electric generator of a fluid pressure operated motor, driving connections between said motor and generator, a conduit conducting fluid to said motor, a valve in said conduit to shut off the supply of fluid to said motor, a circuit, means for operating said valve in response to voltage conditions in said circuit, and a fluid-pressure-controlled valve responsive to fluid pressure in said conduit between said valves for regulating the fluid supplied to said motor, a consumption circuit and means responsive to

voltage conditions in the first mentioned circuit for alternately connecting said consumption circuit with the first mentioned circuit and with said generator.

4. In an emergency electric generating set, the combination with an electric generator of a fluid pressure operated motor, driving connections between said motor and generator, a conduit conducting fluid to said motor, a valve in said conduit to shut off the supply of fluid to said motor, a circuit, means for operating said valve in response to voltage conditions in said circuit and a needle valve responsive to fluid pressure in said conduit for regulating the fluid supplied to said motor, a consumption circuit and means responsive to voltage conditions in the first mentioned circuit for alternately connecting said consumption circuit with the first mentioned circuit and with said generator.

5. In an emergency electric generating set, the combination with an electric generator of a fluid-pressure-operated motor, driving connections between said motor and generator, a conduit conducting fluid to said motor, a valve in said conduit to shut off the supply of fluid to said motor, a circuit, means for operating said valve in response to voltage conditions in said circuit, a valve for regulating the fluid supplied to said motor, and means for preventing seating of said regulating valve.

6. In an emergency electric generating set, the combination with an electric generator of a fluid-pressure-operated motor, driving connections between said motor and generator, a conduit conducting fluid to said motor, a valve in said conduit to shut off the supply of fluid to said motor, a circuit, means for operating said valve in response to voltage conditions in said circuit, a fluid-pressure-controlled valve for regulating the fluid supplied to said motor, and means for preventing seating of said regulating valve.

7. In an emergency electric generating set, the combination with an electric generator of a fluid-pressure-operated motor, driving connections between said motor and generator, a conduit conducting fluid to said motor, a valve in said conduit to shut off the supply of fluid to said motor, a circuit, means for operating said valve in response to voltage conditions in said circuit, a needle valve for regulating the fluid supplied to said motor, and means for preventing seating of said regulating valve.

8. In an emergency electric generating set, the combination with an electric generator, of a water wheel, driving connections between said generator and wheel, a nozzle through which water is projected to said water wheel, a reciprocable needle valve within said nozzle to cause the opening of said nozzle to be increased or diminished, means for preventing seating of said needle valve, a source of water supply for said nozzle, a conduit from said source to said nozzle, a valve in said conduit to shut off water from said wheel, a water operated cylinder having its piston connected with the last mentioned valve, means including a valve mechanism and pipes for alternately connecting the chambers in the cylinder on opposite sides of the piston, with the source of water supply, and connect the space in the cylinder on one side of the piston with a drain when the space on the other side of the piston is connected with the water source, an electric circuit and an electromagnet connected to said circuit and operatively related to said valve mechanism.

9. In an emergency electric generating set, the combination with an electric generator, of a water wheel, driving connections between said generator and wheel, a nozzle through which water is projected to said water wheel, a reciprocable needle valve within said nozzle to cause opening of said nozzle to be increased or diminished, means for preventing seating of said needle valve, a source of water supply for said nozzle, a conduit 10 from said source to said nozzle, a valve in said conduit to shut off water from said wheel, a water operated cylinder having its piston connected with the last mentioned valve, means including a valve mechanism and pipes for alternately con-

necting the chambers in the cylinder on opposite sides of the piston, with the source of water supply, and connect the space in the cylinder on one side of the piston with a drain when the space on the other side of the piston is connected with the water source, an electric supply circuit and an electromagnet connected to said circuit and operatively related to said valve mechanism, a consumption circuit and means including switching mechanism operated by the said piston for alternately connecting said consumption circuit with the said supply circuit and with said generator. 5 10
